(Cl. D34—15)

To all whom it may concern:

Be it known that we, Lebert E. Blue and Verlin F. Hodges, citizens of the United States of America, residing at Montezuma, in the county of Parke and State of Indiana, and Indianapolis, in the county of Marion and State of Indiana, respectively, have invented a new, original, and ornamental Design for an Amusement Car, of which the following is a specification, reference being had to the accompanying drawing, forming a part thereof.

In the drawing:

We claim:

The ornamental design for an amusement car, as shown.

LEBERT E. BLUE.
VERLIN F. HODGES.
